UNITED STATES PATENT OFFICE.

WILLIAM L. HARDER, OF BIRMINGHAM, ALABAMA.

NOISELESS RAILWAY-CROSSING.

1,271,312.

Specification of Letters Patent.

Patented July 2, 1918.

Application filed January 18, 1918. Serial No. 212,441.

To all whom it may concern:

Be it known that I, WILLIAM L. HARDER, a citizen of the United States of America, residing at Birmingham, in the county of Jefferson and State of Alabama, have invented certain new and useful Improvements in Noiseless Railway-Crossings, of which the following is a specification.

This invention relates to a noiseless railway crossing adapted to present a continuous rail to support the wheels of street cars and trains in traversing the crossing from any direction.

The object of my invention is to provide a simple and positive mechanism adapted to be actuated by the flanges of approaching wheels to automatically adjust the movable track elements of the crossing into position to present a continuous rail for the passage of the wheel.

More particularly it is the object of my invention to divide each crossing rail proper into relatively slidable sections, the two sections which converge toward each crossing corner being pivotally connected to a bell crank interposed between the crossing rails, and the diagonally opposite bell cranks being cross connected so as to produce the requisite movement of all crossing rail sections simultaneously.

A further object of my invention is to design the crossing rails with tapered elongated heads at their ends adjacent to the track rails so shaped as to be engaged and shifted laterally by the wheel flange with a movement sufficiently positive to open not only to shift them but also to shift into proper position the other crossing rail sections with which they are connected.

My invention also comprises the various details of construction and arrangements of parts, which in their preferred embodiment only are illustrated in the accompanying drawings, in which:—

Figure 1 presents in plan my improved street railway crossing with the cover plate partly broken away to illustrate the bell crank construction.

Fig. 2 is a sectional view taken on the broken section line 2—2 of Fig. 1.

Fig. 3 is a sectional view taken on the section line 3—3 of Fig. 1.

Similar reference numerals refer to similar parts throughout the drawings.

As illustrated, the crossing is shown connecting the track rails 1, 2, 3 and 4 forming one track with the rails 5, 6, 7 and 8 forming the crossing track. The ends of these several rails are inserted in and connected by bolts 9 to corner brackets 10 which in turn are connected by bolts 11 to the main bed plate 12. These brackets are rectangular castings and at their apexes are recessed to receive manganese inserts 13. The several crossing rails forming continuations of the various track rails being identical in construction only one need be described.

Each crossing rail comprises two sections 14 and 15 which are similar except for their end portions 16 which are shaped to lap along the longitudinal center line of the rail and have their ends beveled so as to avoid joints at right angles to said center line. Thelapping ends 16 are complementary and together form a continuation of the crossing rail in all positions but are chamfered on their adjacent top edges to avoid their being swaged by the pounding of the wheels. At its free end each section

comprises a head 17 disposed opposite one side of the adjacent manganese insert 13 and having an outward extension inclined relatively to such insert in a direction away from the adjacent track rail. This gives the head a wedging contact face 18 which at its end farthest from the crossing is sufficiently spaced from the track rail to prevent the wheel flange ever riding over the same. It is contemplated that the approaching wheel flanges will, when the crossing rails require adjustment thereby, contact with these wedging faces 18 and shift the near transverse crossing rail sections toward each other and away from the manganese inserts, thus affording a clear path for the succeeding wheel flanges. This movement of the near crossing rail sections is imparted by each to its respective bell crank 19, one of which at each corner of the crossing is pivoted to rock about a vertical bearing pin 100

20 which also serves to connect to the bed plate 12 the cover plate 21. Each end of the bell crank is rounded and inserted in a socket 22 in the two adjacent crossing rail sections 14 and 15, care being taken to avoid any appreciable lost-motion in such joint. Each bell crank will therefore connect the adjacent angularly disposed crossing rail sections 14 and 15, and as a crossing rail section 14 or 15 is shifted by the approaching wheel flange, its co-related crossing rail section 15 or 14 will be moved toward the approaching wheel and against the manganese insert so as to close the open track joint at that point. In order to simultaneously produce similar and correspondingly closed joints at the other corners of the crossing each bell crank is provided with an arm 23 disposed in convenient position 20 to be connected by a rod 24 to the corresponding arm of the diagonally opposite crank 19. One of the connecting rods 24 is bolted to the underface of the arms 23 which it connects, and the other rod 24 is 25 bolted to the upper face of the arms which it connects, and thus the two arms clear as they work under the cover plate 21, which leaves ample working clearance for them.

30 In order to confine sections 14 and 15 of each crossing rail to a straight line movement, these rail sections have dove-tail bases 25 which are received between and guided by two angle bars 26 which are bolted to 35 the base plate and have their upturned faces sloped to conform to the sloping sides of the rail bases. The marginal edges of the cover plate are sloped downwardly at 27 to engage and rest on the top edge of the 40 inner guide plates 26. I also provide four inverted U-shaped cover plates 28, each of which has one down turned flange 29 resting on the top edge of the adjacent outer 45 guide plate 26 and having its outer down turned flange 30 seated in a longitudinal groove in the bed plate to which the cover plate is screwed by cap screws or bolts 31, there being one of these plates alongside the outer edges of each pair of crossing rail 50 sections.

In operation, it will be noted that the crossing rail sections between the track rails 1, 2 and 3, 4, stand in position with their heads 17 spaced from the manganese inserts 55 18, sufficiently to clear the wheel flanges while the heads 17 of the other rail sections stand in position engaging their respective manganese inserts, thus closing the crossing joint for wheels approaching on the rails 5, 6, 60 or 7, 8, as the latter will ride from the rails across the brackets and over the inserts onto the crossing rails and over their lapped portions 16 across the other manganese inserts

and brackets onto the main track beyond and in making such passage there will be no jolting or jarring on the wheels due to open joints in the crossing. Should a street car approach the crossing on the tracks 1, 2, or 3, 4, the approaching wheel flanges will engage the wedging faces 18 of the near crossing rail heads 17 and will force the latter laterally away from the manganese inserts so as to permit the passage of the wheel flanges. In thus forcing the near rail heads inwardly, the connected bell cranks 19 will 70 be rocked and will immediately draw the crossing rail sections ahead of the approaching wheels toward the latter and into contact with the manganese inserts, thus closing the near joints while the corresponding 80 closure of the far joints will be effected through the operation of the cross connecting rods 24. The sections of the crossing rails are positively connected and positively moved by the wheels and under any ordinary 85 operating conditions could not interfere with the passage of the wheel flanges in normal course over the crossing.

This invention is not intended to be restricted in scope to the specific embodiment 90 shown, but contemplates such modifications as come within the spirit and scope of the claims.

Having thus described my invention, what I claim as new and desire to secure by Letters Patent, is:—

1. In an automatic continuous railway crossing comprising in combination with the intersecting track rails, a base structure to which said rails are made fast, sectional crossing rails connecting the opposite track rails, each sectional track rail comprising two sections having their near ends provided with extensions forming a lap-joint parallel with the crossing rail and having their remote ends provided with wedge heads adapted to be engaged and moved by the flanges of approaching car wheels, guides on the base to confine the sections of each crossing rail to alining travel, bell cranks pivoted 100 on said base near each corner of the crossing, said bell cranks having their ends rounded 105 and inserted in sockets in the two adjacent crossing rail sections, and operating rods disposed diagonally of the crossing and directly connecting diagonally opposite pairs of bell cranks to cause the latter to move together to produce reverse movements of corresponding crossing rail sections, as and for the purposes described.

2. In a continuous railway crossing, sectional crossing rails having the sections of each crossing rail with its adjacent sections lapped for parallel sliding movement, means to guide said sections in their alining movements, heads on the remote ends of the sec-

tions of each crossing rail which are disposed to be engaged and moved by the approaching wheels, sockets in the sides of crossing rail sections at each corner of the crossing, 5 a bell crank having rounded ends inserted in the sockets of said adjacent pair of crossing rail sections, the diagonally opposite bell cranks having similarly disposed crank ex-

tensions, and diagonal connecting rods, each having an adjustable connection to said 10 cranks on diagonally opposite bell cranks.

In testimony whereof I affix my signature.

WILLIAM L. HARDER.
